MULLION SOCKET

Edward C. Hallock, Summit, N.J.

Application December 14, 1956, Serial No. 44,200

Term of patent 14 years

(Cl. D13—1)

Figure 1 is a perspective view of a mullion socket showing my new design;

Figure 2 is a side elevational view of the mullion socket; and

Figure 3 is a rear elevational view of the mullion socket.

I claim:

The ornamental design for a mullion socket, as shown.
